(57) **CLAIM**

The ornamental design for a credenza, as shown and described.

DESCRIPTION

FIG. 1 is a perspective view of a credenza according to this invention;

FIG. 2 is a front view of the credenza shown in FIG. 1;

FIG. 3 is a right side view of the credenza shown in FIG. 1, the left side view being a mirror image thereof;

FIG. 4 is a top view of the credenza shown in FIG. 1;

FIG. 5 is a bottom view of the credenza shown in FIG. 1;

FIG. 6 is a perspective view of an element of the credenza shown in FIG. 1;

FIG. 7 is a front view of the element shown in FIG. 6;

FIG. 8 is a left side view of the element shown in FIG. 6;

FIG. 9 is a right side view of the element shown in FIG. 6;

FIG. 10 is a top view of the element shown in FIG. 6; and,

FIG. 11 is a bottom view of the element shown in FIG. 6.

The broken lines form no part of the claimed design.

1 Claim, 11 Drawing Sheets
